JOHN J. COMER, OF CHICAGO, ILLINOIS, ASSIGNOR TO AUTOMATIC ENUNCIATOR COMPANY, OF CHICAGO, ILLINOIS, A CORPORATION OF ILLINOIS.

DIFFERENTIAL-MICROPHONE REPEATER.

1,137,188.

Specification of Letters Patent. Patented Apr. 27, 1915.

Application filed February 13, 1911, Serial No. 608,386. Renewed September 12, 1914. Serial No. 861,484.

To all whom it may concern:

Be it known that I, JOHN J. COMER, a citizen of the United States of America, and resident of Chicago, Cook county, Illinois, have invented a certain new and useful Improvement in Differential-Microphone Repeaters, of which the following is a specification.

My invention relates to microphone transmitters in general, but more particularly to microphones of the so-called differential type, and especially to differential microphone repeaters for use in loud speaking or other telephone systems.

Generally stated, the object of my invention is to provide an improved and highly efficient differential microphone for use in telephone transmitters, or for use in telephone repeaters, in which the arrangement of the electrodes is simple and effective, and in which the operative connection or stem does not, even when the microphone is used in a repeater, pass through both walls thereof, but only through one, whereby the construction is simplified and the method of applying and regulating the spring tension necessary to the operation of a repeater is rendered more satisfactory than heretofore, as will hereinafter more fully appear.

To the foregoing and other useful ends, my invention consists in matters hereinafter set forth and claimed.

In the accompanying drawings—Figure 1 is a view of one side of a differential microphone repeater with the casing thereof removed to show the construction. Fig. 2 is a similar view of another side of said repeater. Fig. 3 is a front elevation of the repeater shown in Figs. 1 and 2. Fig. 4 is a transverse section through the microphone portion of said repeater on line 4—4 in Fig. 2. Fig. 5 is a similar section on line 5—5 in Fig. 2. Fig. 6 is an enlarged longitudinal section of the forward or microphone end of the repeater shown in Figs. 1 and 2. Fig. 7 is a collective view of the different parts of the microphone box, showing the said parts separated, and some of said parts being in section.

As thus illustrated, and referring more particularly to Figs. 1, 2 and 6, it will be seen that my invention comprises a permanent magnet A of any suitable, known or approved construction. The pole piece a is clamped between the shorter limb a' of

the said magnet and the block a², which latter rests upon the inner side of the longer limb a³ of said magnet. A bracket a⁴ which engages the limb a', and a bracket a⁵ which engages the limb a³, are clamped to the magnet by the screw a⁶, which latter also passes through the block a² and the pole piece a, whereby the structure is drawn tightly together. The pole piece a has a coil or winding a⁷, it being observed that the limb a³ and the pole piece a are about flush at their outer ends. The limb a³ has its end provided with a shoulder a⁸ which serves as a support for the lower edge of the armature a⁹, which latter is held in place on said shoulder by the magnetism of the permanent magnet, the said armature being of such length that its upper end is opposite the pole piece a, and is adapted to be attracted by the latter when the coil or winding is energized by telephonic currents.

The differential microphone box B is suitably secured to the outer ends of the brackets a⁴ and a⁵. The said box comprises a ring-like back plate b of suitable metal, a front plate b' of suitable metal, which plates are connected together by bolts b² and suitably spaced apart by sleeves b³ of suitable insulating material, which sleeves inclose said bolts. The central opening b⁴ in the back plate b is closed by a disk-like sheet of insulation b⁵, and a similar sheet of insulation b⁶ bears against the inner surface of the plate b', in the manner shown. A disk-like sheet of metal b⁷ bears against the insulation b⁵, and a similar sheet of metal b⁸ bears against the insulation b⁶. A carbon plate or diaphragm b⁹ is held against the metal terminal plate b⁷, and a carbon plate b¹⁰ is held against the metal terminal plate b⁸, these two carbon plates serving as stationary electrodes for the microphone. A ring of insulation b¹¹ fits against the inner surface of the carbon plate b¹⁰, and a ring of insulation b¹² rests against the flat surface of the carbon plate or electrode b⁹, these two rings being spaced apart by collars b¹³ that encircle the sleeve b³. The space between these two rings b¹¹ and b¹² is filled with fibrous asbestos b¹⁴, or other suitable material, whereby a chamber is formed at the center of the box for holding the granular carbon b¹⁵, or other suitable material. The plunger-like or movable electrode b¹⁶ is embedded in the center of the mass of gran-

ular carbon, and is of a diameter to engage the inner edge of the ring of asbestos b^{14} , and the said electrode is adjustably secured to the end of the threaded stem b^{17} which extends through an opening b^{18} in the back of the box. This opening is filled with asbestos b^{19} , or other suitable material, to prevent the granular carbon from escaping. The opening b^4 has a flange b^{20} , and upon the shoulder formed by this flange the ends of the spring b^{21} rest and bear during the normal condition of the repeater, and also during its condition while active or in operation. The said spring is adjustably connected to the threaded stem b^{17} which has an eye b^{22} at its outer end. The electrode b^{16} may be of carbon, or other suitable material, and when vibrated serves to alternately vary the distance at each side thereof, it being understood that the circuits of said electrodes may be of any suitable, known or approved character, such, for example, as those commonly employed for differential microphone transmitters.

The lever or arm C is pivotally mounted in a recess c formed in the bracket a^4 , as by a screw c' , and its outer and upper end is controlled by an adjusting screw c^2 that has threaded engagement with an opening in the bracket a^4 , there being a spring c^3 interposed between said arm and bracket, whereby rotation of the screw will move the arm one way or the other. At its lower pivoted end the said arm or lever carries a vertical screw c^4 , and the lower end of this screw carries a tubular portion c^5 that has a slight internal flange at the lower end thereof, which flange has a knife edge and is adapted to support the headed upper end of the lever c^6 . This lever, it will be seen, extends downward to the eye b^{22} of the stem of the movable electrode. A link c^7 connects the said lever with the projection c^8 on the upper end of the armature, the said lever passing through the link, whereby the lever can be moved up and down in the link to change the point of connection therewith, by rotating the screw c^4 . This, of course, will vary the distance between the link and the fulcrum of said lever, which fulcrum is at the point where the lever is supported by the hollow or tubular fulcrum c^5 on the lower end of the screw c^4 , and will vary the leverage. The position of the armature a^6 , relative to the pole piece a , and the tension of the spring b^{21} , are regulated by the screw c^2 , as adjustment of this screw will move the fulcrum of the lever c^6 either toward or away from the microphone box, thus accomplishing the desired adjustment for regulation.

Thus it will be seen that I provide an improved differential microphone repeater in which the stem of the movable electrode extends through only one side of the box, and

in which the latter is of simple and effective construction, and of such character that heavy currents can be carried without danger of over heating or other trouble. The air gap between the armature and its pole piece can be accurately regulated by the adjustment of the screw c^2 , and the screw c^4 can be adjusted to vary the leverage of the lever c^6 in accordance with the stiffness of the spring b^{21} , it being understood that the first or approximate adjustment of these different parts is obtained by properly adjusting the electrode b^{16} and the spring b^{21} on the stem b^{17} , at the time that they are secured thereon by nuts or other suitable devices. The said microphone box can be easily taken apart for the purpose of repair or substitution. It can be filled with the granular carbon after it is fully assembled, and said carbon will then be held in place by the insertion of the asbestos in the space between the two rings b^{11} and b^{12} , in the manner previously described. The spring b^{21} , is, moreover, disposed between the microphone and the magnet mechanism, and is easily removed and put in place. The insulating parts of the microphone box can be of any suitable character, such as mica or fiber or rubber vulcanite, or any other suitable insulating material that can stand considerable heat if it becomes necessary to employ heavy currents.

With the construction shown, it will be observed that the granular carbon at one side of the movable electrode is separated from the granular carbon at the other side thereof. This is by reason of the engagement of the fibrous material b^{14} with the circumference or edges of the said electrode. This engagement does not interfere with the free and proper vibration of the said electrode, and the results, I find, with this construction, are entirely satisfactory.

What I claim as my invention is:

1. In a differential microphone repeater, a microphone box provided with a movable stem for the operation thereof, a magnet provided with an armature, a connection between the armature and said stem, and a spring opposing the action of said armature, applied to said stem at a point between the armature and box.
2. In a differential microphone repeater, a microphone box provided with a movable stem for the operation thereof, a magnet provided with an armature, a connection between the armature and said stem, a spring opposing the action of said armature, applied to said stem at a point between the armature and box, and means for regulating the tension of said spring.
3. In a differential microphone repeater, a microphone box provided with a movable stem for the operation thereof, a magnet provided with an armature, a connection be-

- between the armature and said stem, a spring opposing the action of said armature, applied to said stem at a point between the armature and box, said spring consisting of 5 a flat strip of spring metal mounted transversely on the said stem, and means for engaging the ends of said spring.
4. In a differential microphone repeater, a microphone box provided with a movable 10 stem for the operation thereof, a magnet provided with an armature, a connection between the armature and said stem, and a spring opposing the action of said armature, applied to said stem at a point between 15 the armature and box, the said connection between the stem and armature comprising a lever.
5. In a differential microphone repeater, a microphone box provided with a movable 20 stem for the operation thereof, a magnet provided with an armature, a connection between the armature and said stem, and a spring opposing the action of said armature, applied to said stem at a point between 25 the armature and box, the said connection between the armature and the stem consisting of a variable leverage connection.
6. In a differential microphone repeater, a microphone box provided with a movable 30 stem for the operation thereof, a magnet provided with an armature, a connection between the armature and said stem, and a spring opposing the action of said armature, applied to said stem at a point between 35 the armature and box, there being a lever in the connection between the stem and armature, a fulcrum for said lever, and means for shifting said fulcrum to regulate the air gap of said armature and the tension 40 of said spring.
7. In a differential microphone repeater, a microphone box provided with a movable stem for the operation thereof, a magnet provided with an armature, a connection 45 between the armature and said stem, and a spring opposing the action of said armature, applied to said stem at a point between the armature and box, the said microphone box having a back plate with a central opening 50 therein, which opening is provided with a flange for engaging the ends of said spring.
8. In a differential microphone repeater, a microphone box provided with a movable 55 stem for the operation thereof, a magnet provided with an armature, a connection between the armature and said stem, and a spring opposing the action of said armature, applied to said stem at a point between 60 the armature and box, said microphone box being closed circumferentially by a filling of fibrous material, and having a movable or plunger-like electrode, the circumference of which is engaged by the inner edges of 65 said filling of fibrous material.
9. In a telephone amplifier, a microphone transmitter comprising a variable resistance box, a diaphragm and a movable stem secured to said diaphragm, an electromagnet and an armature therefor, a lever pivoted at one end, a connection at an intermediate point of said lever to said armature, and a connection from the opposite end to said stem, and a spring opposing the action of said armature applied to said stem 70 at a point between the armature and the box.
10. In a telephone amplifier, a microphone transmitter comprising a resistance box and a diaphragm, an electromagnet 80 and an armature therefor, a lever extending substantially parallel to said diaphragm, a fulcrum for one end of said lever, means for adjusting said fulcrum for regulating the leverage, a connection from said lever to said diaphragm, a stem connected to said lever and said armature, and a second connection from said lever to said armature, and a spring opposing the action of said armature applied to said stem at a point 85 between the armature and said diaphragm.
11. In a telephone amplifier, a microphone transmitter comprising a variable resistance box, a diaphragm and a movable stem secured to said diaphragm, an electromagnet 90 and an armature therefor, a lever pivoted at one end, a link connection at an intermediate point of said lever to said armature, and a connection from the opposite end to said stem, and a spring opposing the action of 95 said armature applied to said stem at a point between the armature and the box.
12. In a telephone amplifier, a microphone transmitter comprising a resistance box and a diaphragm, an electromagnet and an armature therefor, a lever extending substantially parallel to said diaphragm, a fulcrum for one end of said lever, means for adjusting said fulcrum for regulating the leverage, a link connection from said lever to said diaphragm, a stem connected to said lever and said armature, a second connection from said lever to said armature, and a spring opposing the action of said armature applied to said stem at a point between 100 the armature and said diaphragm.
13. In a telephone amplifier, a microphone transmitter, a movable central electrode therefor, a lever, a connection from said electrode to the lever, a fulcrum for said lever, a pivoted support on which said fulcrum is adjustably mounted, an electromagnet, an armature therefor, a connection from said armature to said lever, and means for adjusting said support about its axis, the adjustment of the fulcrum on said support serving to vary the leverage, and the adjustment of the said support serving to vary the air gap between said magnet and armature. 105
14. In a telephone amplifier, a microphone 110
- 120
- 125

transmitter, a movable central electrode therefor, a lever, a connection from the lever to said member, a fulcrum for said lever, a pivoted support on which said fulcrum is adjustably mounted, an electromagnet, an armature therefor, a connection from said armature to said lever, and means for adjusting said support about its axis, the adjustment of the fulcrum on said support serving to vary the leverage, and the adjustment of the said support serving to vary the air gap between said magnet and armature.

15 15. In a telephone amplifier, a microphone transmitter, a movable central electrode therefor, an electromagnet, an armature therefor, a lever, a link connection from the electrode to the lever, said connection being secured to said electrode, a connection 20 from the lever to the armature, a fulcrum for said lever, and means for adjusting said fulcrum to regulate the air gap between said magnet and armature.

25 16. In a telephone amplifier, a microphone transmitter, a movable central electrode therefor, a lever connected to said electrode, an electromagnet provided with an armature for operating said lever, means for changing the leverage, and pivoted means 30 for mechanically regulating the tension of said electrode and the air gap between said magnet and armature.

35 17. In a telephone amplifier, a microphone transmitter, a movable central electrode therefor, a lever connected to said electrode, an electromagnet provided with an armature for operating said lever against the tension of said electrode, a screw for moving said lever longitudinally for changing 40 the leverage, and a screw for mechanically regulating the tension of said electrode and the air gap between said magnet and armature.

18. In a telephone amplifier, a microphone transmitter, a movable central electrode 45 therefor, an electromagnet, an armature therefor, a lever pivoted at one end, a link connection from the opposite end of said lever to said electrode, and a link connection at an intermediate point of said lever to said armature.

19. In a telephone amplifier, a microphone transmitter, a movable central electrode therefor, a polarized electromagnet, an armature therefor, a lever pivoted at one end, 55 a link connection from the opposite end of said lever to said electrode, and a link connection at an intermediate point of said lever to said armature.

20. In a telephone amplifier, a microphone 60 transmitter, a movable central electrode therefor, an electromagnet, an armature therefor, a lever extending substantially parallel to said electrode, a fulcrum for one end of said lever, and means for adjusting 65 said fulcrum for regulating the leverage, a connection from said lever to said electrode, and a second link connection extending from said lever to said armature.

21. In a telephone amplifier, a microphone 70 transmitter, a movable central electrode therefor, an electromagnet, an armature therefor, a lever extending substantially parallel to said electrode, an adjustable fulcrum for one end of said lever, a connection 75 from the opposite end of said lever to said electrode, and a connecting link extending from an intermediate point of said lever to said armature.

Signed by me at Chicago, Illinois, this 80
9th day of Feb. 1911.

JOHN J. COMER.
